LACE

Henry Giebel, New York, N. Y.

Application December 3, 1953, Serial No. 27,881

Term of patent 14 years

(Cl. D47—6)

To all whom it may concern:

Be it known that I, Henry Giebel, a citizen of the United States of America, residing in New York city, county of New York, and State of New York, have invented a new, original, and ornamental Design for a Lace, of which the following is a specification, reference being had to the accompanying drawing, forming part thereof, wherein the figure on the drawing is a plan view of a piece of lace, showing my new design.

I claim:

The ornamental design for a lace, substantially as shown.
